DESIGN FOR A DEVICE FOR HOLDING CAPSULES, PILLS, AND THE LIKE

Leroy F. Lustig, Shaker Heights, Ohio

Application May 21, 1943, Serial No. 110,250

Term of patent 3½ years

(Cl. 83—1)

To all whom it may concern:

Be it known that I, Leroy F. Lustig, a citizen of the United States and a resident of Shaker Heights, county of Cuyahoga, and State of Ohio, have invented a new, original and ornamental design for Device for Holding Capsules, Pills, and the like, of which the following is a specification, references being had to the accompanying drawing, forming a part thereof.

In said annexed drawing:

Fig. 1 is an elevational view of a device for holding capsules, pills, and the like, showing the opaque side of my new design.

Fig. 2 is an elevational view of the other side thereof showing the transparent window.

Fig. 3 is a transverse section taken on the line 3—3 of Fig. 2.

I claim:

The ornamental design for a device for holding capsules, pills, and the like, substantially as shown and described.

LEROY F. LUSTIG.
